UNDER-THE-COUNTER RACK

Richard L. Linquist, Minneapolis, Minn.

Application February 5, 1947, Serial No. 726,573

2 Claims. (Cl. 211—119)

1

This invention relates to under-the-counter racks, and particularly to welded wire racks, suspended from under side of counter, removably mounted, well balanced with easy swinging movement, and arranged so that normally but a small portion extends beyond the counter. The purpose of these racks is to hold a supply of trays, dishes, scoops, pails and other containers of different sizes for meat, oysters, pickles, cottage cheese and the like.

To provide a good supply of such different containers of different sizes, so same are readily accessible and at the same time are kept clean and sanitary, has been a problem. There is usually not enough space available on the counter, so the boxes or crates of containers are set on the floor and exposed to dirt and sawdust from the floor, or taken out of the crate and stacked up in some out of the way place. In the latter case, too much time is wasted in stacking up and going after the containers, and in either case, dirt and dust accumulates in the top container of a stack. The top container is thrown away or the dirt and dust knocked out of it, but too frequently neither one is done. Also, containers in a crate or in a pile somewhere, are difficult to remove quickly, one at a time, and where several different kinds and sizes are needed, confusion results. Much time is wasted, by not having a supply of the different kinds of containers in different sizes, readily available in rear of display case and near a scale, and also in not being able to stack containers direct into a dispensing rack, as they come out of the crate.

One important object is to provide an under-the-counter rack, which will handle different kinds and sizes of containers, all easily accessible and removable, one at a time, which rack, by a swinging movement, may be temporarily moved outward for the purpose, and when released, automatically returns to normal position.

Another object is to provide an under-the-counter rack, that requires a small amount of space, is out of the way, and still can be easily filled direct from a crate, either in place or by convenient detachment.

Another object is to provide an under-the-counter rack, which will keep containers in a clean and sanitary condition, in a position clear of the floor, and also so interior of containers is free from dirt and dust.

Another object is to provide an under-the-counter rack, which although very durable, may be cheaply manufactured.

2

Other objects will be apparent from the description and appended claims.

For a full disclosure of my invention, reference is made to the description following and to the drawings, in which—

Fig. 1 is an elevation view of the rack, showing the different width compartments and the supporting hangers. To avoid confusion, vertical wires at mid-point in each compartment, are omitted.

Fig. 2 is a plan view, which shows arrangement of wires in bottom of rack, hanger arrangement and location of wires omitted in Fig. 1. These wires are shown spaced apart for clarity, but actually are pressed together and welded in practically the same plane as the other wires.

Fig. 3 is a side view of the rack, suspended from under side of counter and in its normal position, as shown by full lines. Projected details are shown at A and B. To avoid confusion, partitions are omitted and only arrangement of wires in end section, is shown. Also, washer under cotter key is omitted to show pivoting more clearly. Broken lines show limit of forward tilt of rack.

Fig. 4 is a side sectional view of the different sized partitions, taken on line 4—4 of Fig. 2. This shows the wire arrangement in the partitions and omits the other details.

In the selected embodiment of my invention, which is hereby disclosed, a rack is made up of No. 8 gage and No. 5 gage wire. A rectangular frame 10 for the front, hangers 11 and pivot rod 12, are No. 5 gage, and all other wires are No. 8 gage. Considerable variation from these sizes, is of course possible and entirely practical. Instead of wire, a rack could of course, except for pivots, be made entirely of flat metal strips. It could also be made almost entirely of wood, plastic or fibre material.

Partitions 13, of different proper depths, are provided at proper intervals, forming compartments to accommodate different sizes of oyster pails, meat trays, dishes or containers in use, and are joined with a bottom 14, which adapts itself to the variations. A use in common of members will be noted, in the joining of partitions, bottom and front, so that good construction is attained with minimum number of members, and without any duplication whatsoever. In the embodiment disclosed, the construction is not quite symmetrical, the compartment on extreme right being larger than that on extreme left. This is to accommodate some containers of a larger size. The construction may be varied to suit particular

cases, other trades, any future new arrangement or any new design of containers, but the proportions disclosed, meet the present general requirement in stores and butcher shops. It will be observed, that intermediate partitions have two intermediate wires 15, while those forming the end frames, have only a single wire 16. The extra intermediate wires are needed, to better position smaller containers in the compartments. In the bottom, intermediate wires 17 provide necessary spacing, to support the different sizes of containers. In the front frame, wires 18 at mid-point of compartments, provide necessary support in that direction. The number and spacing of wires in partitions, bottom and front frame, may need be varied to suit particular cases. If there should be a change in style of dish or container, so that ends are more rounded, then it may be desirable to provide two intermediate wires instead of one in each compartment in the front frame, and that may then require only one instead of two in each of the other partitions. The rectangular frame 10 is formed by butt-welding the two wire ends. Otherwise, wires are lap welded, where they are in crossing or intersecting relation, and all ends are ground smooth, so there are no projections. The construction might of course be butt-welded in whole or in part. Cross pieces 19 and 20 in end partitions or frames, in addition to lap-welding, have loops bent in same as shown in details A and B, and the purpose of which, will be later explained. The pivot rod 12 is lap-welded to the six wires 18 of the front, to stiffen it, and near each end to the rectangular frame 10. The six wires 18, which are lighter, are thereby forced into the same plane as the frame 10, along the line of the pivot rod 12, instead of being in different planes, which for clearness, it was necessary to so show in the drawing.

The hangers 11, constructed in a right hand and left hand manner, have angle bends 21 and 22 at their upper extremities. These angle bends have their ends bent into eye loops, to be engaged by screws to fasten hangers to under side of counter. It will be observed, that the portion of the hangers terminating in the angle bend 22, has a bend at 23 and another bend at 24. These bends bring about a stability in suspension of hangers horizontally, without interference with operation. The hangers are formed into an eye loop 25, at their lower extremities, adapted to engage each end of the pivot rod 12. To maintain shape and rigidity, spot welds 26 are inserted between the two portions of the hanger. If there should be an increase in weight of containers, so greater stiffness is required, one or more struts may be welded between the two portions of the hanger, preferably above its engagement with the rack. Washers 27 are welded to the eye loops 25, and hangers are held in place by easily removable cotter keys 28, inserted in drilled holes in pivot rod 12, and resisting thrust of the washers.

An engaging and stop member 29 is attached by welding, to each of cross pieces 19 of end frames in a right hand and left hand manner. These stop members engage the hangers as shown in detail at A, when rack is in normal position. The cross piece 19 besides being welded, is bent into a loop 30 around wire of end frame, to provide smooth engaging action for hanger. The end of cross piece 20 is bent into a loop 31, as shown in detail at B, to act as a stop to engage hanger, so rack will not be tilted

too far in the outward direction and spill the contents. After manufacture is completed, racks and hangers are dipped in paint or enamel. If desired, hot dip galvanizing or electro plating may be provided.

From the foregoing, the operation of the rack should be apparent. The suspension and weight angle are such, that the rack whether fully or partly loaded or empty, will maintain the normal position shown in full lines in Fig. 3. At this angle, the containers will always thrust to the front of the rack, thus always keeping containers in place in an orderly manner. When necessary to gain access to containers or to fill the rack, its nice balance permits of ready oscillation outward, and when unrestrained, it will assume its normal position out of the way under the counter. To prevent tilting too far accidentally or when filling, the stops 31 prevent any further tipping than that indicated by dotted lines in Fig. 3, which it will be observed, is still well above horizontal, so that containers will not fall out. The beveled tops of partitions are an aid to accessibility, and with the additional space afforded in middle of rack, because of shallower depth of partitions, good clearance is available to reach into rack to remove containers from any compartment. The time saved by use of the rack is evident. In a meat market, the counter is occupied by the display case, except for a narrow ledge in back, which is not sufficiently wide to store pails, trays or containers. In stores, otherwise, the counter is ordinarily in full use. In either case, it becomes necessary to store such containers in a place, which is usually neither accessible nor sanitary. With my rack located under a scale or at a dispensing point, the containers are always within reach, and at the same time are kept clear of saw dust and rubbish, to which containers in a crate setting on the floor, are subjected. This rack clears the floor, so floor can be swept without interference. Combined with its clearance of the floor, the bottom sets back, so that it is not encountered by the shop keeper's feet. Pails, trays and containers are deposited into the rack directly from their crates, in an upside down position, thereby keeping the inside always clean and sanitary. In using containers directly out of crates, dirt and dust accumulate in the top container of a stack, and it is frequently necessary to discard same. To fill the rack, it is only necessary to pull the top outward, fill and let it drop back into position. It can of course also be easily removed by removing the cotter keys from the pivot rod, filled wherever the stock may be located, and replaced. Although primarily intended as an under-the-counter rack, it may of course be set up anywhere and serve well in dispensing containers.

While I have shown and described a preferred form of my invention, it is obvious that many changes, which are within the scope of my invention, will be apparent to those skilled in the art. I therefore desire to be limited only by the scope of the appended claims.

What I claim is:

1. A tilting, under-the-counter, wire rack comprising, a substantially rectangular front frame, a pair of end frames, having tops tapered toward the front, a plurality of varyingly spaced partitions of varying depths, also having tops tapered toward front, and a bottom, said front frame, end frames, partitions and bottom being joined together, by common members, to form an open top rack, vertical wires secured to said front

frame intermediate of partitions, a horizontal pivot rod secured to outer side of front frame and intermediate wires, and having drilled holes with removable cotter keys at each end, two vertical hangers, each consisting of a length of wire, bent at its midpoint into an eye loop, and adapted to engage one end of pivot rod, and into angle bends with loops at the other ends to accommodate wood screws into under side of counter, a washer secured concentrically to said eye loop for smooth bearing against cotter key, each of said hangers having its two legs secured together for a substantial distance adjoining said eye loop, the rearward of said legs having bends rearwardly and outwardly to increase stability, two stops on each of said end frames engaging the vertical hangers and limiting tilting of rack on the hangers, one stop maintaining a normal nearly vertical position, and the other stop an outwardly inclined position for filling the rack with containers.

2. An under-the-counter, metal store fixture comprising, a front frame, two end frames, a plurality of partitions, a bottom and two vertical hangers with pivots and stops, said front frame, two end frames, partitions and bottom being joined together, by common members, to form an open top rack, said front frame being substantially rectangular in shape, and having vertical members secured thereto intermediate of said

partitions, said end frames having upper ends beveled toward said front frame, said partitions being also similarly beveled at their upper ends, and being of such varying widths and being varyingly spaced as to provide compartments of different sizes, said bottom being of varying width and spacing of members, since it is joined to and in conformance with width of partitions, said hangers, each consisting of a loop bent and having its end secured for firmly supporting said rack from under side of counter, said pivots for said hangers, and a pair of said stops secured to each of said end frames, to maintain substantially vertical and horizontal positions for said rack.
